UNITED STATES PATENT OFFICE.

HERBERT FOSTER, OF NEW HAVEN, CONNECTICUT, ASSIGNOR TO BRANDT CASHIER COMPANY, OF CHICAGO, ILLINOIS, A CORPORATION OF ILLINOIS.

COUNTING DEVICE.

1,128,594.

Specification of Letters Patent. Patented Feb. 16, 1915.

Application filed September 9, 1911. Serial No. 648,561.

To all whom it may concern:

Be it known that I, HERBERT FOSTER, a subject of Great Britain and Ireland, residing at New Haven, in the county of New Haven and State of Connecticut, have invented certain new and useful Improvements in Counting Devices, of which the following is a specification.

This invention relates in general to counting devices and aims to produce a registering device adapted for attachment to a change machine, the device being constructed to register the number of individual coins of varying value requisite to the discharge 15 of a pay-roll or the like.

Change machines, constructed to deliver the requisite number of coins of the various denominations to make up the amount of change required upon the operation of a 20 push button or key indicating the amount, have been in common use prior to my present invention which is designed as an attachment for such a machine to register the number of coins of each denomination which 25 will be required in paying off a large number of bills, pay slips or the like.

Change machines of the character above indicated usually comprise a series of ejecting devices adapted to be projected from 30 the body of the machine to deliver from a magazine containing coins of various denominations the requisite number of coins designated by the particular push button which is operated and my present invention 35 is intended to be substituted in place of the coin magazine so that each set of registry wheels will be actuated by one of the coin ejecting devices upon the actuation of a push button, whereby the number of 40 coins designated by the particular push button will be registered and the total number of coins designated by successive actuations of a number of push buttons will be counted and the total exposed to the view of the 45 operator.

My invention will be best understood by reference to the following description when considered in connection with the accompanying drawings illustrating one preferred embodiment thereof.

Referring to the drawings—Figure 1 is a side elevation of a change machine with the side plate removed, showing my improved registering device attached thereto, 50 the side plate of said registering device be-

ing removed to show the interior thereof; Fig. 2 is a sectional elevation of the registering device viewed from the front; and Fig. 3 is a sectional view taken on the line 3—3 of Fig. 2.

On the drawings, 5 designates generally a change machine which may be of any well known or preferred type, the one disclosed, however, being generally known to the trade as the "Brandt" machine. The 65 frame of this machine is supported upon suitable legs 6 and 7 and carries at its front end a change pocket or hopper 8 into which the coins are delivered when the machine is used for making change. Journaled in 70 the sides of the frame 5, are a series of rockers 9, each of which comprises a bar or shaft extending transversely of the machine which is normally held in the elevated position shown in Fig. 1 by tension springs 10 75 secured at one end to the shafts and at their other ends to the frame of the machine. The ends of the shaft are bent as shown so that the shaft proper is offset from the bearings 9' and each shaft is provided with a 80 downwardly extending arm 11 which is pivotally connected with a forwardly projecting link 12. The forward end of each link is guided in its longitudinal movements by guides 13 and carries an upwardly projecting head 14 to which is pivotally connected at 15 a coin ejecting device 16. The rockers are actuated by the feet 17 of edgewise arranged plates or bars 18, each carried by a shank 19 which is guided in its vertical 90 movements by a flat plate 20 through which the shank projects. Expansion springs 21 serve to normally retain the shanks in elevated position and the push buttons 22 mounted thereon, in alignment. This general type of change machine is well known and since it constitutes no part of my present invention the detailed construction need not be specifically described except in so far as may be necessary for an understanding of its operation in connection with the attachment which I have combined therewith. It will be sufficient for the purposes of this application to simply state that each rocker is adapted to project a coin ejector 105 16 forwardly into a coin magazine to eject a coin therefrom into the hopper 8. The coin magazine is not shown on the drawings, the same having been replaced by my improved registering device. The magazine,

however, as is well known, consists of a series of vertically arranged slots in which coins of different denominations are exposed and each actuation of an ejector will 5 remove the lowermost coin from one of the slots. Each of the push button shanks 19 is equipped with one or more feet 17 to rock as many of the rockers 9 as may be necessary to eject such coins as will total in value 10 the number shown on the particular push button 22 which is depressed. It will be understood that my invention may be used in connection with other types of change-making machines and that the particular 15 construction of the change machine is not material so far as this application is concerned.

Upon the front of the change machine in the position normally occupied by the coin 20 magazine, I have detachably mounted a casting 23 in which is journaled a shaft 24 provided at one end with a knurled operating knob 25. The shaft proper is supported in suitable uprights or standards 26 having 25 forwardly projecting lugs or ears 27 in which is fixedly supported a rod 28. Upon the rod 28 I have mounted a series of elongated bearings 29 which are provided with 30 downwardly projecting arms 30, 31, 32, 33, 34, 35 and 36, respectively. The lower ends of these arms are disposed in alinement with the forward ends of the coin ejectors 16. Upon the shaft 24 I have mounted a series 35 of sets of registry wheels, which sets are designated on the drawings as 40, 41, 42, 43, 44, 45, 46 and 47, each set preferably comprising, as shown, three or more wheels provided with numbers, the wheels in each set being adapted to register units, tens, hundreds, etc., as is customary with various types of counting devices. Each of the 40 bearings 29 is provided with an upwardly projecting arm or lever 48 which has pivoted at its upper end a pawl 49 adapted to engage 45 with the unit wheel of a set of registry wheels. An ear 50, projecting forwardly from each of the bearings 29, is connected by a spring 51 with the base of the frame, whereby the pawls are normally held in re- 50 tracted position shown in Fig. 1, and a second spring 52, connected with the projecting end of each pawl and its corresponding ear 50, holds the free end of the pawl in engagement with its respective unit wheel. A 55 spring 53 is provided for each registry wheel to yieldingly retain the same in any position to which it may have been rotated on the shaft 24. It will be evident that when a coin ejector is projected it will en- 60 gage the lower end of one of the downwardly projecting levers and push the same outwardly, thereby imparting a rearward movement to the pawl 49 carried upon its arm 48 and rotating its respective unit wheel 65 one step. When the ejector is withdrawn

by the return spring 10, the pawl and levers will be restored to normal position by the springs 51 and 52. While it will be evident that as many sets of registry wheels may be employed as there are registering devices on a change machine and that the unit wheel of each set may be moved forward one step only at each operation of its particular ejector, I have shown in the present instance a registering mechanism constructed and 70 adapted for attachment to a particular change machine which discharges coins to the value of fifty cents only and is capable of delivering change to the amount of one dollar. This type of machine, therefore, is constructed to deliver fifty cent pieces, quarters, 75 dimes, nickels and pennies. The registering device, therefore, is adapted to register the number of the above coins delivered. In the particular arrangement shown, the set of 80 registry wheels 40 are adapted to register fifty cent pieces; the set 41, twenty-five cent pieces; the sets 42 and 43, ten cent pieces; the set 44, five cent pieces; and the sets 45, 46 and 47, pennies. The coin ejector of the 85 machine with which this registering device is adapted to be employed, which engages with the arm 37, discharges, when used as a change machine, two pieces at each actuation thereof, consequently in order to accurately 90 register and count the number of coins required, it is necessary that the unit wheel of the set 45 move two steps at each operation of its ejector. In order that this may be accomplished the bearing 38 is mounted in 95 a lower plane than the bearings 29 so that the length of the arms 37 and 48 are diminished and increased, respectively, thus imparting a longer stroke to this particular arm 48 and moving the unit wheel of the set 100 45 two steps instead of one at each operation. If preferred, however, all of the bearings may be mounted in the same plane and the unit wheel of the set 45 may be marked only 105 with alternate figures as 2, 4, 6, etc., in which 110 instance, movement of the wheel one step will register two coins.

The sets of registry wheels are loosely mounted on the shaft 24 and are adapted to be returned to initial position upon one 115 revolution of said shaft in a counter clockwise direction looking at Fig. 3. Such a connection between the wheels and the shaft is well known and need not be explained in detail. I have, however, designed novel 120 mechanism for locking and releasing the shaft 24 which will now be explained.

A pin 50' projects downwardly from the shaft 24 when in normal position to be engaged by a lever 51' pivoted on a pin 52' 125 mounted in the upright 26 and provided with a locking slot 53' into which the lower end of the pin 50' projects. Stop pins 54 and 55 limit the swinging movement of the lever 51' on its pivot. The lower or shorter 130

end of the lever is provided with a curved tail 56 adapted to be operated by pin 59 mounted on a rotatably knurled knob 58. A spring 60 holds the parts normally in the 5 position shown in Fig. 3, the shaft 24 being held against rotation by engagement with the lever 51'. When it is desired to reset the registry wheels the knurled knob 58 is turned in a counter clockwise direction, 10 viewing Fig. 3, to elevate the tail 56 and withdraw the opposite end of the lever from engagement with the pin 50', the shaft 24 may then be rotated by means of the knob 25 in a counter clockwise direction until the 15 pin 50' engages with the rear face of the shoulder 59, the registry wheels being thereby returned to zero position. The shaft may then be turned in a clockwise direction until the pin 50' is again brought into 20 engagement with the notch 53', whereupon the shaft will be automatically locked against rotation with the various parts in position for operation of the device in the manner previously described.

25 While I have shown and described a preferred embodiment of my invention it will be apparent that various forms of the invention may be employed with counting machines of various types and that the invention is not restricted to the registering 30 of coins of a less denomination than one dollar, but that the same idea may be extended to machines adapted to register coins or currency of any denomination. Furthermore, the invention is not restricted to the 35 construction and arrangement of the parts as shown and described, but various changes in the mechanical details of the invention may be resorted to without departing from 40 the spirit or sacrificing any of the material advantages thereof.

I claim:

1. The combination of a change machine comprising a plurality of coin ejecting devices and a series of operating buttons, and a registering mechanism adapted to replace the coin magazine of said machine and comprising a set of registry wheels for each coin ejecting device and a pivoted lever positioned in the path of each coin ejecting device and connected with a corresponding set of registry wheels whereby the sets of wheels will be actuated at each operation of their respective coin ejecting devices.
- 55 2. The combination of a change machine, and a detachable registering mechanism, said mechanism adapted to replace the coin maga-

zine of said machine, comprising a plurality of sets of coaxially mounted registry wheels, a plurality of pivotally mounted levers having their lower ends arranged in the path of the coin ejecting devices of the change machine, a pawl mounted upon the upper end of each of said levers in position to engage with the unit wheels in said sets and means for maintaining said pawls in engagement with their respective wheels whereby upon operation of the change machine said wheels will be actuated to register the number of coins designated by said coin machine. 70

3. The combination of a change machine having operating keys for ejecting coins from the machine, and a removable device for computing change totals temporarily replacing the coin magazine of said change machine and operable through the agency of the operating keys of said change machine. 75

4. The combination of a change machine provided with a plurality of coin ejecting devices, and a removable device for computing change totals temporarily replacing the coin magazine of said change machine and provided with registering mechanisms interposed in the path of travel of and operable by said ejecting devices. 80

5. The combination with a change machine, comprising a plurality of coin ejecting devices and keys for operating the same, of a counting device removably connected 90 with said machine and adapted to replace the coin magazine of the machine, said counting device comprising a plurality of sets of registering wheels and a pivotally mounted operating lever for each set of 95 registering wheels, said levers being positioned in the path of movement of said coin ejecting devices when the counting device is substituted for the coin magazine of the machine. 100

6. In combination with a coin ejector structure comprising a plurality of coin ejectors and means for selectively actuating said ejectors, a support on said structure for normally receiving coin magazine mechanism, and a unitary counter structure comprising a plurality of counters and adapted for detachable application to said support in place of the coin magazine structure and to be operated by said ejectors. 105
